SOUND REPRODUCING DEVICE

Semi Joseph Begun, Cleveland, Ohio, assignor to
The Brush Development Company, Cleveland,
Ohio, a corporation of Ohio

Application July 31, 1941, Serial No. 404,773

18 Claims. (Cl. 179—100.41)

My invention pertains to sound reproducing devices and more particularly to reproducers for use with records which have been cut with a laterally undulating groove.

It has been recognized that the process of producing laterally cut records introduces for a record modulated by a sinusoidal frequency, a plurality of constrictions in the width of the cut groove to the plane cutting surface of the cutter being always perpendicular to the axis of the unmodulated groove. The frequency of these constrictions is twice the frequency of the signal recorded on the record. When a stylus having a point of finite radius of proper size to fit in the unconstricted portions of the groove and in contact with both groove walls, traverses the constricted portions of the groove it is forced up, and as the constriction passes, the stylus settles back into the unconstricted portion of the groove. This is termed the "pinch effect." For low signal frequencies the "pinch effect" probably does not introduce serious distortion in the reproduced signal but for higher signal frequencies it does. The distortion arises from the fact that the stylus does not maintain contact with both side walls of the groove at all times. At low frequencies the force of gravity on the stylus acts to maintain the stylus in engagement with both side walls. But at higher frequencies the force of gravity does not accelerate the stylus in a downward direction quickly enough, and the groove bottom "drops away" from the stylus as the record turns, thereby causing the stylus tip to rattle loosely in a higher and wider portion of the groove. This inability of the stylus tip to be always coupled to both walls of the groove may cause distortion in the reproduced signal.

It is an object of my invention to obviate the foregoing difficulties.

It is a further object of my invention to substantially obviate the results of the "pinch effect" to provide a device which will reproduce signals with little distortion.

An object of my invention is to provide a reproducer structure which will follow the undulations in the record groove over a wide frequency range and with substantially uniform response.

Another object of my invention is to provide a reproducer which is subject to movements in more than one plane and which will effectively convert movements in substantially only one plane into an electromotive force.

A further object of my invention is to provide a reproducer which will give substantially undis-

torted response even though subject to severe "pinch effect" conditions.

Still another object of my invention is to provide a reproducer having a stylus system of low mass but sufficient stylus force for good response.

Another object of my invention is to provide a reproducer having a low stylus force on a record and having a substantial percentage of that force arising from a biasing force.

10 It is another object of my invention to provide a reproducer having a low total stylus force on the record and having the low total force arising from a combination of low stylus mass and a slight stylus biasing force.

15 A further object of my invention is to provide a reproducer which is responsive to stylus motions in substantially only one plane.

Other objects and a fuller understanding of my invention may be had by referring to the following detailed description and claims, taken in conjunction with the accompanying drawing in which:

Figure 1 is a plan view on a small scale of a phonograph turntable and a pickup arm.

25 Figure 2 is a sectional view taken along line 2—2 of Figure 1 and showing a form of my invention.

Figure 3 is a sectional view taken along line 3—3 of Figure 2.

30 Figure 4 is a sectional view of a modified form of my invention.

Fig. 5 is a sectional view taken along line 5—5 of Figure 4.

35 Figure 6 is an isometric view of a modified form of my invention.

Figure 7 is a sectional view taken along line 7—7 of Figure 6.

Figure 8 is an isometric view of another form of my invention, and

40 Figure 9 is an isometric view of still another form of my invention.

My invention is adapted to be used with a phonograph which is illustrated in Figure 1 as comprising a base 10, a turntable 11 mounted on the base 10 and adapted to rotate with respect thereto, and a pickup arm 12 secured to the base 10 and adapted to pivot with respect to the base and with respect to the turntable 11. Equipment such as a motor 9 to drive the turntable, amplifiers, and other such equipment necessary to convert record undulations into music, speech, etc. may be mounted inside the base 10. A phonograph record 13 may be mounted on the turntable 11 and as the turntable rotates the continuous spiral undulatory groove 14 which is on the

surface of the record causes a stylus 15, (Fig. 2) which is mounted in the pickup arm 12, to move laterally. The movement of the stylus 15 causes movement of an electro-mechanical transducer unit, 16, (Fig. 2) thereby establishing an electro-motive force.

The electro-mechanical transducer unit 16 may be made of several slabs of Rochelle salt crystal 17 and 18 cemented together to form a "twister" unit. Electrodes 19 and 20 are provided on surfaces of the crystal slabs 17 and 18, and leads 21 and 22 are electrically connected to the electrodes, the lead 21 engaging the electrode 19 and the lead 22 engaging the electrode 20. The unit 16 is illustrated unwaterproofed to show the internal construction, and it is to be understood that the unit may be covered by one or more layers of a waterproofing material.

The transducer unit 16 is held in a receptacle 27 in the pickup arm 12 by means of damping pads 28 and 29, and by means of shims 26, and a sliding wedge 25. A screw 24 holds the wedge in place. The damping pad 28 is positioned at the top edge of the transducer unit 16 and is adapted to substantially prevent movement of the top edge of the unit 16 with respect to the pickup arm 12, and the damping pad 29 is positioned along the center portion of the transducer unit 16 and extends from the top pad 28 substantially to the bottom of the unit 16 thereby establishing a central neutral axis along the section line 3—3 which is substantially immovable. A resilient drive wire 30 which may be a flattened hollow tube or a solid strip having greater width than thickness, is connected at one end to the bottom of the transducer unit 16 and at the other end to the stylus 15. Movement of the stylus 15 due to the undulations in the groove 14 in the record 13 is in a direction substantially normal to the surface of the cutting plane 2—2. This movement causes a twisting of the transducer unit 16 about the neutral axis and establishes an electromotive force substantially in accordance with the motion of the stylus 15. The electromotive force appears at the leads 21, 22 which extend through a slot 31 in a boss 32 to one end of an attaching clip 33. The attaching clip 33 is connected at its center to the wall 32 of the receptacle 27 by a screw 34, and a connecting wire 35 is attached to the other end of the attaching clip 33 thereby establishing an electrical connection between the transducer unit 16 and the wire 35. The connecting wire 35 extends back through the arm 12 and into the base 10 where it is connected to an amplifier.

Connected to the other wall 36 of the receptacle 27 by means of screws 37 is a spring 38. The spring 38 is adapted to bias the stylus 15 toward the record 13. A damping pad 39 may be provided between the spring 38 and the stylus 15. The stylus point is subject to desirable lateral movements due to the undulations in the record groove, and is subject to undesirable vertical movements due to "pinch effect." The drive wire 30 is shaped to have a stiffness factor in a first direction which is sufficiently high to effectively transmit the desirable lateral stylus movements to the transducer unit 16, and to have a stiffness factor in a second direction which is sufficiently low to substantially prevent transmission of the undesirable vertical stylus movements to the transducer. In other words the drive wire is relatively rigid in a horizontal direction and is relatively flexible in a vertical direc-

tion. The vertical flexibility permits the stylus to respond to the "pinch effect" to reduce wear and tear on the record and stylus, and the downward bias provided by the springs 38 and 39 causes the stylus to be coupled to both of the side walls of the record groove to prevent stylus chatter which causes distortion in the reproduced signal. Under stationary conditions the stylus force is a function of the effective or unbalanced weight of the pickup arm. This weight will deflect the stylus drive wire 30 and the spring 38. The amount of deflection will be proportional to the effective weight and will establish in the resilient drive wire 30 and in the spring 38 a downwardly directed biasing force. Under operating conditions acceleration forces will arise from the "pinch effect" and from the effective stylus and spring mass, and the acceleration forces will vary the stylus force. Care must be taken that the acceleration force oppositely directed to the biasing force does not exceed the biasing force. The ability of a pickup having no spring bias to follow the "pinch effect" is substantially independent of the weight of the stylus. Accordingly, a stylus force arising from a spring bias between the pickup arm and the stylus will cause the stylus to more closely follow the record groove than a force arising directly from the pickup arm.

Several means for establishing the downward bias may be used. In Figure 2 two spring units 38 and 39 are provided, one of which may be the stylus drive wire. In Figure 3 the spring bias is provided by the drive wire 30 alone, and in Figure 6 damping means 40 may contribute to the bias provided by the drive wire 30.

Figure 4 illustrates a device in which the transducer unit 16 is replaceably connected in a housing 41 by means of the top damping pad 28 and a bottom damping pad 42, and the housing 41 is secured in the receptacle 27 by means of screws 43 which thread into the receptacle wall 32. A side plate 44 (Figure 5) is connected to the side of the housing 41 by means of screws 45, and a bottom plate 46 having a hole through which the stylus projects is connected to the housing 41 by means of screws 47.

Figure 8 illustrates another form of my invention in which the stylus 15 is connected to the transducer unit 16 by means of a plurality of wires 50, 51 which are arranged to brace each other in a horizontal direction to effectively transmit the horizontal stylus motion to the transducer unit 16, and to provide vertical flexibility to substantially prevent the transfer of vertical stylus motion to the unit 16. The wire 50 is looped around the top of the stylus 15 and is attached to a band 52 connected to the crystal unit 16, and the wire 51 is looped around near the bottom of the stylus 15 and is also connected to the band 52. Solder or other connection means may be provided to connect the wires 50, 51 to the stylus 15. Vertical movement of the stylus 15 will cause the wires 50, 51 to bend, but horizontal movement in the direction of the arrow will cause a tension to be put in one side or the other of each of the wires 50, 51 thereby twisting the transducer unit 16.

Figure 9 illustrates a waterproofed transducer unit 55 of the bender type with its associated leads 21, 22, and the damping pad 53 which holds one end of the unit against movement. A connecting clip 54 attaches the stylus drive wire 30 to the crystal unit 16.

My pickup arm 12 (Figure 2) is provided with

a downwardly curved end portion 57 which extends over the stylus 18. The end portion 57 provides protection for the stylus, the stylus drive wire 30, and the spring member 38; and is equipped with a conformable shoe portion 58. The shoe portion 58 engages the surface of the record 13 and takes part of the unbalanced weight of the arm 12 off of the stylus thereby reducing the stylus force to a point which will allow the addition of a biasing force from the spring 38 without increasing the total stylus force to a point where it is excessive. It may be a felt or chamois piece which is adapted to conform slightly to the record grooves to aid the stylus in causing the arm to pivot with respect to the record as the record turns.

Although I have described my invention with a certain degree of particularity, it is to be understood that the present disclosure has been made only by way of example and that numerous changes in the details of construction and the combination and arrangement of parts may be resorted to without departing from the spirit and the scope of the invention as hereinafter claimed.

I claim as my invention:

1. In a pickup arm for use with a record having an undulatory groove, piezo-electric transducer means for converting a motion into an electromotive force, a stylus in engagement with said record and subject to motions from said undulatory groove, driving means directly connecting said stylus only to said transducer and free from engagement with any other means and adapted to transmit said stylus motions to said transducer, said driving means providing a bias between said transducer means and said stylus to couple said stylus to said record groove to cause said stylus to follow said undulatory groove substantially at all times.

2. In a pickup adapted for use with a record having a laterally cut groove, a Rochelle salt piezo-electric generator unit adapted to establish an electromotive force upon being moved, stylus means directly connected to said generator unit and free from engagement with any other means but having a stylus point for engagement with said record groove and subject to lateral movements and also subject to vertical movements due to "pinch effect", said stylus means being comparatively rigid in a first direction to transmit said lateral movements to said transducer and comparatively flexible in a second direction to substantially prevent transmission of said vertical movements, and said stylus means establishing a spring bias between said generator unit and said stylus point to maintain said stylus point in engagement with said record groove substantially continuously throughout the playing of the record.

3. Translating means for use with a laterally cut record to convert undulations in the record into electrical impulses comprising, a piezo-electric crystal unit which is bendable in a first direction and substantially non-bendable in a second direction, means for mounting said crystal unit, a stylus in engagement with said record and adapted to be actuated laterally by said undulations and also adapted to be actuated substantially vertically, and driving means connecting said stylus to said crystal unit, said driving means being comparatively stiff in a first direction and comparatively flexible in a second direction, said driving means in said first direction effectively transmitting the lateral movements of said stylus

10 to the said crystal unit to cause said crystal unit to bend in said first direction and generate an electromotive force, and said driving means in said second direction and the substantially non-bendability of the crystal unit in said second direction co-operating to substantially prevent the said vertical actuations of the stylus from bending the crystal unit to prevent the generation of an electro-motive force for vertical movements of the stylus.

4. Translating means for use with a record to convert undulations in the record into electrical impulses comprising, supporting means, a Rochelle salt type crystal unit having a first and a second edge portion and having one of said edge portions restrained by said supporting means over substantially its entire length, and having the other of said edge portions restrained by said supporting means to establish an axis substantially normal to the plane of said record, said unit being adapted to establish an electromotive force upon being actuated about said axis, stylus means in engagement with said record and subject to desired motions in a first direction resulting from said record undulations and to undesired motions in another direction, means for connecting said stylus means to one of said edge portions of said unit to actuate said unit about said axis as said stylus is moved in said first direction by the undulations in the said record, said connection means being flexible to reduce the transmission of the undesired motions to said crystal unit and to reduce the force on the stylus.

5. In a pickup unit adapted to be connected to a pickup arm and adapted to be actuated by a record having undulatory grooves, a transducer unit connected to said arm and adapted to establish an electromotive force upon being actuated, stylus means adapted to engage said record and subject to movement due to said undulatory grooves, first and second flexible driving means connected to said stylus means and to said transducer unit, said first and said second driving means providing for movement of said stylus with respect to said transducer unit in a direction substantially perpendicular to said record, and said first and said second driving means mutually bracing each other to cause a lateral movement of said stylus to actuate said transducer unit.

6. In a pickup arm having a flexible stylus adapted to engage a surface and partially support said pickup arm on said surface, shoe means connected to said pickup arm and adapted to engage said surface and cooperate with said flexible stylus to support said pickup arm.

7. In a pickup arm pivotal with respect to and for use with a revolvable record having a continuous spiral undulating groove; an electro-mechanical transducer means including flexible stylus means connected to said pickup arm and in engagement with said continuous spiral undulating groove and adapted to change the undulations of said groove into a varying electrical potential, and guide means connected to said pickup arm and in engagement with said spiral groove, said guide means cooperating with said stylus means to support said pickup arm and to cause said pickup arm to pivot with respect to said revolvable record.

8. A pickup arm pivotal with respect to and for use with a record having a series of undulatory grooves, comprising, an electro-mechanical transducer connected to said pickup arm and adapted to establish an electromotive force substantially in accordance with motions, a stylus in engage-

ment with the undulatory grooves of said record and subject to lateral and vertical motions, driving means connected to said stylus and connected to said transducer, said stylus and said driving means being adapted to transmit motions from said undulatory grooves to said transducer, said driving means effectively transmitting lateral motions to said transducer and reducing the amount of vertical movement which is transmitted to said transducer, and shoe means connected to said pickup arm and in engagement with said record, said shoe means and said stylus means cooperating to cause said pickup arm to pivot with respect to said record.

9. In a pickup arm pivotal with respect to and for use with a record having a continuous spiral groove; a vertically flexible stylus means connected to said pickup arm and in engagement with said continuous spiral groove for only partially supporting the unbalanced weight of said pickup arm, and shoe means having a conformable portion connected to said pickup arm and in engagement with said record, said conformable portion of said shoe means engaging and extending over several turns of said spiral groove and cooperating with said stylus means to support the said unbalanced weight of said pickup arm and to cause said pickup arm to pivot with respect to said record.

10. A pickup arm pivotal with respect to and for use with a record having a series of undulatory grooves comprising, an electromechanical transducer connected to said pickup arm and adapted to establish an electromotive force substantially in accordance with motions in a first direction, stylus means relatively stiff in said first direction and relatively flexible in a second direction in engagement with the undulatory grooves of said record and in engagement with said transducer, and adapted to transmit forces according to motions in said first direction from said undulatory grooves to said transducer, said stylus means bending in said second direction to reduce the transfer of forces according to motions in said second direction, and shoe means connected to said pickup arm and in engagement with said record, said shoe means and said stylus means cooperating to support said pickup and to cause said pickup arm to pivot with respect to said record.

11. Translating means for use with a record to convert undulations in the record into electrical impulses comprising, a Rochelle salt type crystal unit, means for mounting said unit to establish an axis which is perpendicular to the surface of said record and about which the said unit is adapted to twist to generate an electromotive force, stylus means in engagement with said record and connected to said unit and adapted to twist said unit as said undulations in said record cause said stylus means to move, and mechanical means for establishing a bias to couple said stylus to said record, and damping means connected to said mounting means and in engagement with said stylus means for damping the vertical movements thereof.

12. Translating means for use with a laterally cut record to convert undulations in the record into electrical impulses comprising, a piezo-electric crystal unit which is bendable in a first direction and substantially non-bendable in a second direction, means for mounting said crystal unit, a stylus in engagement with said record and adapted to be actuated laterally by said un-

dulations and also adapted to be actuated substantially vertically, and driving means supporting said stylus means from and directly connecting said stylus to said crystal unit, and said driving means being free from engagement with other supporting means, said driving means being comparatively stiff in a first direction and comparatively flexible in a second direction, said driving means in said first direction effectively transmitting the lateral movements of said stylus to the said crystal unit to cause said crystal unit to bend in said first direction and generate an electromotive force, and said driving means in said second direction and the substantially non-bendability of the crystal unit in said second direction cooperating to substantially prevent the said vertical actuations of the stylus from bending the crystal unit to prevent the generation of an electromotive force for vertical movements of the stylus, and damping means in engagement with the driving means for damping the vertical movements of the driving means.

13. Translating means for use with a record to convert undulations in the record into electrical impulses comprising, supporting means, a Rochelle salt type crystal unit having a first and a second edge portion and having one of said edge portions restrained by said supporting means over substantially its entire length, and having the other of said edge portions restrained by said supporting means to establish an axis substantially normal to the plane of said record, said unit being adapted to establish an electromotive force upon being actuated about said axis, stylus means in engagement with said record and subject to desired motions in a first direction resulting from said record undulations and to undesired motions in another direction, means for connecting said stylus means to one of said edge portions of said unit to actuate said unit about said axis as said stylus is moved in said first direction by the undulations in the said record, said connection means being flexible to reduce the transmission of the undesired motions to said crystal unit, and damping means connected to said supporting means for damping the movements of said connection means in the direction of the desired movement.

14. In a pickup arm having flexible resilient stylus means including a tip portion adapted to engage a surface, said stylus means being adapted to partially support said pickup arm on said surface, shoe means directly connected to said pickup arm and adapted to engage said surface and cooperate with said flexible stylus means to support said pickup arm, and other resilient means engaging said flexible stylus means for applying a bias thereto in the direction of said surface.

15. A device as set forth in claim 14 in which said other resilient means also damps the movement of the flexible stylus means.

16. In a pickup arm, transducer means connected to said pickup arm and adapted to establish an electromotive force upon being actuated, stylus means for engaging a record having undulations, and subject to desirable motions in a first direction and also subject to undesirable motions in a second direction, and drive means comprised of a flattened hollow tube connected to said stylus and to said transducer for transmitting the stylus motions to the transducer, said flattened hollow tube being oriented to more effectively transmit the desired motions and less effectively transmit the undesired motions, said

stylus means and said drive means from the point of engagement between said stylus tip and a record to the point where said drive means engages said transducer means being free from engagement with any other means.

17. In a pickup arm pivotable with respect to and for use with a record; a piezoelectric transducer connected to said arm, stylus means having a record engaging tip and including flexible resilient drive means directly connecting said tip to said transducer and free from engagement with other supporting means, said stylus means being adapted to engage said record to support only a portion of the unbalanced weight of said pickup arm, and other resilient means connected 10 15

to said pickup arm and in engagement with said stylus means for supporting a portion of the unbalanced weight of said pickup arm without stressing said piezoelectric transducer.

18. In a pickup arm; a piezoelectric transducer comprised of a fragile crystal, flexible stylus means connected to said fragile crystal, said stylus means when in engagement with a surface partially supporting the unbalanced weight of said pickup arm and stressing said fragile crystal, and auxiliary resilient supporting means connected to said pickup arm for supporting the remainder of the unbalanced weight of said pickup arm without stressing said fragile crystal.

SEMI JOSEPH BEGUN.
